UNITED STATES PATENT OFFICE.

JOHN WILLIAM REA WILLIAMSON, OF WESTERTON, SCOTLAND.

SLUICE OR GATE VALVE.

Application filed December 14, 1920. Serial No. 430,645.

To all whom it may concern:

Be it known that I, JOHN WILLIAM REA WILLIAMSON, a subject of the King of the United Kingdom of Great Britain and Ireland, and residing at Westerton, Dumfriesshire, Scotland, have invented a certain new and useful Improvement in Sluice or Gate Valves, of which the following is a specification.

10 The subject of this invention is a sluice or gate valve the closing of which under the action of a spring is controlled from a remote position.

The present invention consists in the employment of toggle mechanism adapted, when straight, to hold the valve in open position and capable of being bent by means operable from a distance so as to permit the valve to close under the action of 20 the spring.

The invention is illustrated in the accompanying drawings in which Fig. 1 is an elevation partly in section and Fig. 2 is an elevation partly in section at right angles to 25 Fig. 1.

As shown, the valve 1^a fitted to the spindle 1 is urged by a spring 2 towards closed position and is sustained normally in open position by a toggle mechanism comprising 30 upper toggle links 3 pivoted to a cross head 4 secured to the valve spindle 1 and lower toggle links 5 pivoted at 6 on the valve casing 7, and connected at 8 to the upper toggle links. To the connection 8 are attached 35 tripping arms 10 which are connected to a cord or wire 13 wrapping the pulley 14 and operable from a distance. The tripping arms 10 are adapted to swing into an inoperative position in which the outer end of 40 each tripping arm engages a ledge 11 on the valve casing whereby the toggle device is prevented from becoming accidentally bent. For holding the toggle mechanism in substantially straight position slightly beyond 45 the dead centre, there are formed on the valve casing lugs 12 against which about the lower toggle links 5.

It will be understood that, when the valve is to be closed the cord 13 is tensioned, 50 whereby the tripping arms 10 are first brought out of engagement with the ledge 11 and are then moved to bend the toggle.

I claim:—

1. The combination of a valve, a spring for closing the valve, a toggle device serving when substantially straight to hold the valve in open position and means operable from a distance for bending the toggle to permit the spring to close the valve. 55

2. Valve mechanism comprising the combination of a valve, means tending to hold the valve in closed position, and a toggle which when substantially straight holds the valve in open position, and means for bending the toggle to permit the valve to close. 60

3. Valve mechanism comprising the combination of a valve, means tending to hold the valve in closed position, and a toggle which when substantially straight holds the valve in open position, locking means for 70 preventing accidental bending of the toggle, and means for rendering the locking means inoperative and bending the toggle to permit the valve to close.

4. Valve mechanism comprising the combination of a valve, means tending to hold the valve in closed position, a toggle which when in substantially straight position slightly beyond the dead center holds the valve in open position, means for limiting 80 the bending of the toggle beyond this substantially straight position in one direction, and means for bending the toggle in the other direction to permit the valve to close. 85

5. Valve mechanism comprising the combination of a valve, a spring tending to hold the valve in closed position, a toggle which when in substantially straight position beyond the dead center holds the valve in open position, a stop limiting the bending 90 of the toggle beyond this substantially straight position in one direction, a tripping arm for preventing accidental bending of the toggle in the other direction, and means for tripping the tripping arm and bending 95 the toggle beyond the dead center to permit the spring to close the valve.

In testimony whereof I have signed my name to this specification in the presence of two subscribing witnesses.

JOHN WILLIAM REA WILLIAMSON.
